Patented May 12, 1914.

UNITED STATES PATENT OFFICE.

ANDREW H. RIDER, OF DETROIT, MICHIGAN.

GAME APPARATUS.

1,096,266.

Specification of Letters Patent. Patented May 12, 1914.

Application filed April 28, 1913. Serial No. 763,955.

To all whom it may concern:

Be it known that I, ANDREW H. RIDER, a citizen of the United States of America, residing at Detroit, in the county of Wayne 5 and State of Michigan, have invented certain new and useful Improvements in Game Apparatus, of which the following is a specification, reference being had therein to the accompanying drawings.

This invention relates to a game apparatus and to an arrangement thereof for reproduction of base ball.

The invention consists in the matters hereinafter set forth and more particularly 15 pointed out in the appended claims.

In the drawings, Figure 1 is a plan view of an apparatus that embodies features of the invention; Fig. 2 is a view in end elevation of the apparatus; Fig. 3 is a view in detail of the tail, enlarged, of a guide pulley; Fig. 4 is a view in detail taken on or about line IV—IV of Fig. 3; Fig. 5 is a view in transverse section through a driving pulley; Fig. 6 is a view in detail of the clip; and Fig. 7 25 is a view in detail of a ball used.

As herein shown a horizontally disposed rectangular plate or field 1 of suitable material on a frame 20, to generally represent a base ball diamond, is arranged with a home 30 base 2, first base 3, second base 4 and third base 5 at each corner and with a pitcher's box 6 in proper relation thereto. An arm 7 is secured on the field with a ball bat 8 swinging on a chain or flexible supporting member from the free end of the arm. 35 Apertures 9 and pegs 10 engaging the same may be used for keeping track and scoring the game. The bat 8 is so suspended as to be readily swung across the home plate 2 and strike a ball, such as indicated at 11, 40 that is thrown by the user on to a block 6 corresponding to the pitcher's box, to bound across the homeplate. The block 6 is arranged to extend below the field board to rest 45 solidly on the table or support that the field is placed on. The ball is preferably of celluloid or like light and elastic material.

An endless flexible carrier or belt 12 surrounds the field 1 and travels on flanged 50 pulleys 13 or guide wheels that are journaled each at a corner of the field. Preferably the member 12 is a flat belt or tape. Clips 14 are mounted upon the belt at such intervals that they all may be brought simultaneously into register with the base. Preferably the clips are in the form of wire loops

whose divergent end portions are riveted or otherwise secured to the belt and whose upper portions are indent and upturned as indicated in Fig. 2 to travel along over the 60 marginal portions of the plate 1 which may be arranged to represent base paths. Suitable figures of players indicated at 15, are provided each with a grooved block 16 that may be set over the upright portion of a clip 65 loop. A guide pulley 17 at the home plate 2 has a crank 18 by which it may be rotated to drive the belt. If preferred, the drive wheel may have spurs as indicated at Fig. 5 for preventing slipping. The bat is disposed 70 to swing above the handle 18. A finger 19 or knock-off member is secured on the member 7 to project over the belt and engage and dislodge figures thereon from the carriers 14 as they approach the home plate. 75

In operation a figure is placed on a clip and is brought to the home plate and a person representing the team "at bat" endeavors to strike a ball bounced on the block or the pitcher's box to pass over the home plate. 80 When the ball is struck the batter advances the figure as far as he can by turning the crank, the other player recovering the ball and endeavoring to put the moving figure "out," under the rules and regulations of 85 the regular game.

Obviously, changes in the details of construction may be made without departing from the spirit of my invention and I do not care to limit myself to any particular 90 form or arrangement of parts.

What I claim is:—

1. Game apparatus comprising a plate representing a base ball diamond with bases at the corners thereof, guide pulleys at each corner of the plate, an endless carrier member traveling on the pulleys, clips secured on the carrier and adapted to overlie the marginal portions of the plate, player figures adapted to be detachably secured on 95 the clips, a bat suspended to swing over one of the bases, and a knock-off member adapted to dislodge figures from the clips as they approach said latter base.

2. Game apparatus comprising a plate 105 representing a base ball diamond with bases at the corners thereof, guide pulleys at each corner of the plate, an endless carrier member traveling on the pulleys, clips secured on the carrier and adapted to overlie the 110 marginal portions of the plate, player figures adapted to be detachably secured on the

clips, means for rotating one of the pulleys to drive the carrier, a bat suspended to swing over one of the bases, and a knock-off member adapted to dislodge figures from the 5 clips as they approach said latter base.

3. Game apparatus comprising a plate representing a base ball diamond with home base, first base, second base and third base at the corners thereof, a pulley journaled 10 at each corner of the plate to turn on an upright axis, a crank for turning the pulley at the home base, an arm secured on the plate adjacent the home base, a bat suspended on the arm to swing above the crank, an endless

carrier traveling on the pulleys, clips on the 15 carrier intent to move over the marginal portions of the plate between the bases, player figures adapted to be detachably mounted on the clips, and a knock-off member on the arm in the path of travel of the 20 figures.

In testimony whereof I affix my signature in presence of two witnesses.

ANDREW H. RIDER.

Witnesses:

C. R. STICKNEY,
ANNA M. DORR.
